UNITED STATES PATENT OFFICE.

JAROME F. BENSON, OF LORENZO, TEXAS.

HOLDER FOR SLIDING DOORS AND WINDOWS.

1,268,671.

Specification of Letters Patent. Patented June 4, 1918.

Application filed April 30, 1917. Serial No. 165,508.

To all whom it may concern:

Be it known that I, JAROME F. BENSON, a citizen of the United States, residing at Lorenzo, in the county of Crosby and State of Texas, have invented certain useful Improvements in Holders for Sliding Doors and Windows, of which the following is a specification, reference being had therein to the accompanying drawing.

- 10 The present invention has reference generally to improvements in that class of inventions known as builders' hardware and more particularly relates to a holder for sliding doors and windows.
- 15 As the primary aim and object this invention contemplates the provision of novel clutch means operably mounted on a base which is adapted to be attached to a sliding member so that the clutch means may co-
- 20 operate with an adjacent stationary member to maintain the sliding member in an adjusted position, the clutch means being constructed so as to operate in either direction so that the sliding member may be moved 25 and is particularly adapted for use on sliding doors and windows.

The invention has for an additional object to provide means for movably mounting the clutch member on the attaching base, re- 30 silent means coöperating with the mounting means and tensioned so as to normally maintain the clutch member in frictional engagement with a stationary object such as a window or door frame.

35 A more specific object of the present invention consists in the provision of means on the base which coöperate with the clutch member for limiting the movement thereof so as to insure an effective frictional en- 40 gagement of the clutch member and to pro- vide means on the head of the clutch mem- ber for aiding frictional engagement of the clutch member and for obviating scarring of the object with which the clutch member 45 is maintained in frictional engagement.

Among the other aims and objects of this invention may be recited the provision of a device of the character mentioned with a view to compactness, and in which the num- 50 ber of parts are few, the construction simple, the cost of production low and the efficiency high.

Other objects as well as the nature, characteristic features and scope of this invention will be more readily apparent from the following description taken in connection

with the accompanying drawings and pointed out in the claims, forming a part of this specification.

The preferred embodiment of the present 60 invention is clearly illustrated in the accompanying drawings, in which:—

Figure 1 is an elevation showing the device attached to a sliding window sash.

Fig. 2 is a front elevation of the same 65 with the cover plate removed, the dotted lines being indicative of the position assumed by the lever in releasing the clutch means.

Fig. 3 is a front elevation of the invention 70 attached to a horizontal sliding door.

Fig. 4 is a sectional detail taken through the clutch head.

Fig. 5 is a perspective detail of the base 75 or attaching plate forming a part of the casing.

Similar characters of reference are em- 80 ployed in all of the above described views, to indicate corresponding parts.

Referring now, more particularly to the 85 accompanying drawings there is provided an attaching base plate 1 formed desirably of metal and of a substantially inverted L-shaped configuration, the respective ends of the long portion of the plate having flanges 2 and 3 formed thereon and approximately at right angles thereto. The lower flange 3 is provided with a slot 4 for a purpose that will presently appear while each of the flanges 2 and 3 are respectively formed with 90 short flanges 5 which project inwardly toward each other and have openings 6 formed therein. Fastening devices 7 serve to removably maintain the base plate in a sub- 95 stantially rigid position on a movable mem- ber such as a window sash 8 as indicated in Fig. 1 or horizontally sliding door 9 as indicated in Fig. 3.

As intimated, improved clutch means have 100 been provided and in the present instance consist of a clutch member embodying a head 10 having a curved outer edge and a straight inner edge from the intermediate point of which projects a shank 11 which is pivotally connected to the outer end 12 of 105 a bell crank lever 13. This bell crank lever is pivoted through the medium of a suitable fastening device 14 to the base plate while the handle portion 15 is arranged through the slot 4 in the flange 3 which serves as a 110 means for limiting the swinging movement of the lever. A rubber strip 16 has the

flange portion 17 thereof arranged in a correspondingly formed groove 18 in the curved edge of the clutch head 10 and serves to facilitate frictional engagement between the 5 head and a window frame 19 as shown in Fig. 1 of a floor or door frame 13 as indicated in Fig. 3. Incidentally, the rubber strip 16 prevents scarring of the object with which the head is in engagement. Coöperating with the shank 11 of the clutch member are limiting members or stops in the present instance in the form of screws 21 mounted on the outer face adjacent the outer edge of the outer portion of the base plate. 10 These stop screws are arranged so as to be engaged by opposite sides of the shank 11 and limit the swinging movement of the clutch member while it is being arranged in frictional engagement with either a window frame or a door frame. 15

In order to normally hold the clutch member in frictional engagement with either a window frame or a door frame as the case may be suitable resilient means have 20 been provided and in the present instance consist of a leaf spring 22, one end of which is rigidly mounted to a fastening device 23 carried by the front face of the base plate while the outer end bears against the handle 25 portion 15 of the bell crank operating lever 13 as indicated by the numeral 24.

Coöperating with the base plate in providing the casing for inclosing the clutch member and the operating means therefor 30 is a cover plate 25 shaped correspondingly to the base plate and removably connected to the short flanges 5 through the medium of suitable fastening devices such as screws 26 the inner ends of which engage the openings 35 6 in the short flanges.

The operation of the invention may be reviewed as follows:

Assuming that the parts have been assembled in the manner described and that 40 the device is applied to a window sash and frame as illustrated in Fig. 1 during the upward movement of the sash the clutch member is held in an inoperative position by moving the handle portion 15 of the bell 45 crank lever 13 toward the frame and obviously during this movement of the bell crank lever about its pivot the clutch member is drawn in close relation with the stop screws. Subsequent to the adjusting of the 50 window sash to a desired height, the handle portion 14 is released and owing to the tension of the leaf spring 22 the lever 13 is moved in a reverse direction about its pivot 14 until the clutch head 10 engages the window frame. The lever striking the adjacent end of the slot, of course, limits the undue outward movement of the clutch member. Slight downward movement of the window sash partially rocks the clutch head 10 until 60 the shank 8 strikes the adjacent pin 21

which prevents further movement of the clutch head. During this rocking movement the clutch head frictionally engages the frame and since it is prevented from further movement the frictional engagement thereof serves to support the sash. Obviously, the operation is the same in Fig. 3 only the clutch head coöperates with the floor or door frame. It is to be understood however that on reverse movement of either the sash or the door the clutch member will move about its pivot a slight extent so that the opposite portion of its curved edge will be correspondingly arranged in frictional engagement with a window frame or door frame 80 respectively to prevent movement in a reverse direction.

It will be understood that the above description and accompanying drawings comprehend only the general and preferred embodiment of this invention and that various minor changes in detail of construction, proportion and arrangement of the parts may be made within the scope of the appended claims and without sacrificing any of the 90 advantages of this invention.

Having thus fully described my invention, what I claim as new and desire to secure by Letters-Patent, is:—

1. A stop of the character described including a casing embodying a substantially L-shaped base plate having flanges on the lower end of the long portion and on the upper side edge of the short portion thereof, the lower flange being provided with a slot, and a cover plate removably connected to the flanges, a clutch member including a head and a shank, a bell crank lever pivotally connected to the base plate and having the outer end pivotally connected to the shank, the handle portion of the bell crank lever being arranged through the slot in the flange and limited in its movement thereby, resilient means mounted on the base plate and bearing against the lever to normally hold the clutch member in frictional engagement with an object, and limiting means mounted on the base plate and coöperating with the shank for holding the clutch head in frictional engagement with an object. 95

2. A stop of the character described including a substantially inverted L-shaped base plate having flanges on the lower end of the long portion and on the upper side edge of the short portion thereof, the lower flange being provided with a slot, a correspondingly shaped cover plate removably connected to the flanges, a clutch member including a head and a shank, means mounted on the head for aiding frictional engagement of the head, a bell crank lever pivotally mounted on the base plate and having the outer end of the short outer portion pivotally connected to the shank, the handle 100

portion of the bell crank lever being arranged through the slot in the lower flange and limited in excessive movement thereby, a leaf spring having one end rigidly connected to the base plate and the opposite end bearing against the handle portion of the lever to consequently normally tension the clutch member, and limiting members

5 mounted on the outer faces of the short portion of the base and adjacent the outer edge 10 thereof and arranged upon opposite sides of the shank to the clutch member so as to be contacted by the shank to hold the head in frictional engagement with an object.

In testimony whereof I affix my signature. 15

JAROME F. BENSON.
